UNITED STATES PATENT OFFICE.

WILLIAM MATHER, OF MANCHESTER, ENGLAND.

APPARATUS FOR DYEING.

SPECIFICATION forming part of Letters Patent No. 662,281, dated November 20, 1900.

Application filed August 28, 1899. Serial No. 728,783. (No model.)

To all whom it may concern:

Be it known that I, WILLIAM MATHER, engineer, a citizen of England, residing at Salford Iron Works, Manchester, in the county 5 of Lancaster, England, have invented certain new and useful Improvements in the Treatment of Textile Materials with Liquids, Vapors, or Gases and Apparatus for that Purpose, (for which I have applied for a patent 10 in Great Britain, dated August 17, 1899, No. 16,730,) of which the following is a specification.

Textile materials, such as yarns or woven fabrics, are sometimes treated with liquids, vapors, or gases for bleaching, dyeing, and other purposes by winding them on perforated hollow cores and causing the fluid, by pumping or otherwise, to pass through them radially from the outside inward or from the inside 20 outward; but it is difficult to secure uniformity of action in all parts of the material when it is treated in this manner. Again, yarns or woven fabrics twisted in rope form are loaded in suitable trucks which are run 25 into closed keirs or chambers through which the fluids are caused to circulate; but in this case also it is difficult to secure uniformity of treatment and to prevent distortion of the fabric, which necessitates subsequent straightening operations.

The present invention relates to an improved method of treating with fluids textile materials, especially woven fabrics, in their full width without twisting or creasing them 35 by means of apparatus which form the subjects of divisional applications. For this purpose the fabric or web to be treated or a set of webs temporarily connected is rolled in its full width without twisting or creasing on a 40 horizontal axis until a roll of convenient size is formed, the rolling being preferably effected in a vessel containing some suitable liquid, which gives the material a preparatory soaking. One end of the roll is arranged to 45 about against a perforated partition which separates the main vessel containing the roll from an end compartment. This compartment communicates with the main vessel by pipes provided with a rotary or other pump 50 and suitable valves by which fluid can be sent either from the main vessel to the compartment or in the reverse direction. In

either case the fluid has to find its way through and between the convolutions of the fabric in streams, which are not radial, but 55 are virtually parallel to the axis of the roll, so that all the convolutions, whether those near to or those far from the axis, receive practically uniform treatment, and this may be further insured by causing the roll to revolve 60 either continually or at intervals. In order to insure the flow parallel to the axis of the roll, the web of fabric before it is rolled should have pieces of impervious material attached to its ends, so that when it is rolled 65 these attached pieces will form internal and external covers, preventing radial flow of the fluid and compelling it to penetrate the whole length of the roll in streams substantially parallel with its axis. Means of heating or cooling the fluid may be combined with 70 the circulating apparatus.

Such being the general character of the present invention, I shall proceed to describe apparatus by which it can be practically carried out, referring to the accompanying drawings, it being understood that to this apparatus I make no claim in the present application.

Figure 1 is a longitudinal, and Fig. 2 is a 80 transverse, section of one form of the apparatus. Fig. 3 is a longitudinal section of a modified form, and Fig. 4 is a part longitudinal section of another modification. Fig. 5 is a longitudinal section. Fig. 6 is a transverse section. Fig. 7 is an end view, and Fig. 8 is a side view, showing the apparatus applied to trucks in closed chambers or keirs.

Referring first to Figs. 1 and 2, *a* is a cylindrical vessel provided with a door *b*, which 90 can be tightly closed. In this vessel is mounted a fluted mandrel *c*, which passes through a stuffing-box at one end of the vessel and has its end part screw-threaded to receive a nut *d*. This mandrel carries a perforated disk 95 or partition *e*, which can slide on but must turn with the mandrel and has its edge bearing against a fixed shoulder *f*. The door *b* being opened, the end of a web or fabric or of several webs temporarily connected together 100 by stitching or otherwise being attached to the mandrel, this is caused to revolve, so as to wind the web or webs on it in a number of convolutions, the fabric being thus formed

into a roll, the length of which is equivalent to the width of the web. The vessel is partly charged with the liquid required to saturate the fabric, which is thus soaked while it is being wound on the mandrel. The door *b* being then closed, the vessel is charged with additional liquid for soaking the fabric, and after a time the nut *d* is turned, while the mandrel is prevented from turning, so as to draw the end of the roll of fabric close against the partition *e*, which is thus pressed against the shoulder *f*. Through pipes *g* at each end of the vessel liquids can be pumped or steam or gases can be forced into and through the vessel, having to pass on their way longitudinally through and between the successive convolutions of the fabric in streams substantially parallel to the axis. In order that all parts may receive uniform treatment, the roll can be either continuously or from time to time caused to revolve by turning the mandrel and partition. After sufficient treatment the vessel can be emptied, and then the door *b* being opened the fabric can be unwound and detached from the mandrel.

As shown in Fig. 3, the perforated disk or partition *e* forms one wall of a separate chamber communicating with a central pipe *h*, which takes the place of one of the pipes *g*. In this case the screw is on a spindle *i*, fitting a nut fixed in the mandrel.

As shown in Fig. 4, the partition *e* is stationary, in which case when the roll of fabric has to be turned it is first, by turning the nut *d*, separated a little from the partition, so that it is free to turn.

In many cases it is desirable to treat larger rolls in a keir, which has comparatively small capacity for liquid, so that small quantities of fluid can be successively applied to the fabric, each fresh supply being free from the impurities which tend to accumulate in a large quantity of fluid when that is repeatedly circulated through the apparatus and fabric. For this purpose I arrange the apparatus as shown in Figs. 5, 6, 7, and 8. The keir *m* receives two trucks, each having on it a large horizontal roll of fabric, and the size of the keir is such that there is comparatively little space around the rolls and at the ends, and in order to reduce as much as possible the capacity for fluid I provide in the lower part of the keir two channels *p*, in which the truck-wheels run. Each truck has bearings for a mandrel *c*, on which the fabric is rolled before the trucks are introduced into the keir, the fabric being preferably drawn through tanks in

which they are soaked. At the right end of the one mandrel and the left end of the other is a chamber *q*, each fronted by a perforated disk *e*. At the closed end of the keir is a spindle *r*, having on it a hand-wheel *s*, by which it can be turned, and a screw-sleeve *t*, by which it can be moved lengthwise, clutched in a sleeve *u*, which passes through a stuffing-box and has a clutching-flange made in segments engaging behind segments projecting inward in the end of the mandrel. At the other end of the keir where the door is there are corresponding parts; but the spindle instead of being carried on a fixed bracket has its bearings in a cross-bar *v*, which, the spindle being withdrawn, can be raised out of the way when the door is opened to allow the trucks to enter or leave the keir. At the side of the keir about the middle of its length is fixed a box which communicates with the circulating-pipe and has two tubes *x*, provided with lateral openings and having stems which pass through stuffing-boxes and can be turned by a suitable wrench or handle. When the trucks are in position in the keir, the tubes *x* are screwed into lateral holes in the chamber *q*, which are thus put in communication with the pump. The circulating-pipe also communicates with the body of the keir by two lateral inlets *y* near the ends of the keir, the branches leading to these preferably passing through a chamber adapted for heating or cooling. By turning the screws *t* the mandrels are advanced, pushing the ends of the rolls close up to the perforated disks *e*, with which the mandrels engage by clutches *z*, so that when the rolls are turned by turning the wheels *s* the disks *e* turn with them.

Having thus described the nature of this invention and the best means I know for carrying the same into practical effect, I claim—

The herein-described method of treating textile fabrics with fluids, which consists in rolling the fabric in its full width, without folding or twisting, revolving the roll of fabric, and simultaneously causing the fluid to flow through the roll, between the convolutions thereof and in a direction parallel with the axis of the roll, as specified.

In testimony whereof I have hereunto set my hand in presence of two subscribing witnesses.

WILLIAM MATHER.
